OVERCOLLAR FOR OVERCOAT

Herman L. Zimmerman, Brooklyn, N. Y.

Application March 9, 1956, Serial No. 570,595

7 Claims. (Cl. 2—84)

This invention relates to detachable overcollars for overcoats, topcoats and similar articles of apparel.

An object of the invention is to provide a novel and improved, detachable overcollar adapted to be removably secured to the inside neck portion of an overcoat or the like so as to overlie the regular collar of said coat, said detachable collar being convertible into a hat or hood, in conjunction with the regular coat collar, by detaching it from the said neck portion and fastening it to the free edge of the regular coat collar.

Another object of the invention is to provide a novel and improved overcollar in accordance with the above, which does not require any alteration of the regular coat or collar thereof, except the incorporation of cooperable fastening elements by which the overcollar may be secured in its different operative positions.

A further object of the invention is to provide an improved detachable overcollar as above characterized, which is extremely simple in its construction and economical to fabricate.

A feature of the invention resides in the provision of an improved overcollar of the above type, which may be easily and quickly adapted or converted to its uses as either an auxiliary collar or a hat or hood.

Another feature of the invention resides in the provision of an improved overcollar in accordance with the foregoing, which may be faced with fur or other collar-facing material, thereby to provide a fur or other distinctive collar on an overcoat which otherwise is provided only with the usual or ordinary collar.

Other features and advantages will hereinafter appear.

In the drawings accompanying this specification, similar characters of reference indicate corresponding parts wherever possible in the several views, in which:

Figure 1 is a top view of the improved collar of the present invention, shown in flat position with the several pieces or components thereof superposed one on the other.

Fig. 2 is a view like Fig. 1 but of the reverse or underside of the overcollar.

Fig. 3 is a perspective view of the overcollar used as a hat.

Fig. 4 is a front view of the overcollar, shown attached to an overcoat and folded or rolled over the regular coat collar thereof.

Fig. 5 is a perspective view of the overcollar attached to the free edge of the regular coat collar and extended or unfolded so as to constitute a hood, for covering the head of the wearer.

Fig. 6 is a transverse section taken through the collar and the garment.

Referring to Figs. 1 and 2, the improved overcollar of the present invention comprises an outer sector-shaped piece of material 10 to which there is attached an inner or under, sector-shaped piece of material 11. The pieces 10 and 11 are arranged in superposed relationship as shown, and are secured together along one set of corresponding convex edges 12 in any suitable manner, as for example by stitches or other fastening means.

2

As clearly seen in Fig. 2, the under piece 11 is smaller than the top or outer piece 10, and has end edges 13 and 14 which fall short of the end edges 15 and 16 of the larger piece.

5 For the purpose of securing the overcollar in various positions on an overcoat, the larger or top piece 10 is provided with releasable fastening means, which may be advantageously in the form of button holes 17 (shown herein as three in number).

10 Referring to Fig. 4, there is illustrated an overcoat 18 having buttons 19 secured inside the neck portion of the usual collar, said buttons being so disposed that they may be passed through the button holes 17 to secure the overcollar to the inside of the neck portion of the coat. 15 When so secured, the overcollar may be folded or rolled downward so that the piece 10 is exposed, as shown in Fig. 4, thereby giving the appearance of an ordinary collar of a coat.

Further, in accordance with the invention, the regular 20 coat collar of the coat 18, indicated at 20 in Fig. 5, may be provided on its underside with buttons 21 arranged to be received in the button holes 17 of the piece 10, thereby to enable the latter to be releasably attached to the free edge of the collar 20, as shown. With this arrangement, the overcollar may advantageously constitute a hood, for disposition about the head of the wearer of the coat.

Further, in accordance with the invention, the free edge 25 23 of the piece 11 is provided with cooperable fastener means, as for example mating zipper elements, thereby to enable one-half of said edge to be releasably attached to the other half, thereby to close over the top of the hood as illustrated in Fig. 5.

For the purpose of holding the pieces 10 and 11 in 30 their normal, superposed relationship when the overcollar is worn as a collar, separable fastening means 25, as for example, snap fasteners or the like, may be provided on the pieces 10 and 11, thereby to secure the free edge portions of the piece 11 to the adjoining surface portions of the piece 10, as shown in Fig. 2.

40 For the purposes of the invention a fabric facing 26 may be provided on the piece 10 in such a way as to be exposed when the overcollar is constituted as a collar, as seen in Fig. 4.

45 It will be readily understood that, by the present invention, I have provided a novel and improved detachable overcollar for overcoats, topcoats and the like, which overcollar is extremely simple, economical in construction, and adapted to constitute either an additional collar for the overcoat, or else in conjunction with the regular collar of the overcoat, a hat or hood which may be disposed about the head of the wearer of the overcoat. The detachable overcollar may be easily and quickly converted from one use to the other, and may be easily arranged 50 by virtue of the snap fasteners, zipper elements, and buttons and button holes.

Variations and modifications may be made within the scope of the claims, and portions of the improvements may be used without others.

60 I claim:

1. The combination of an overcoat having a permanently attached collar on which there is a free edge provided with separable fastening means, and having other separable fastening means inside its neck portion; a detachable overcollar for said overcoat, comprising a pair 65 of segmental-shaped pieces of material disposed in superposed relation; means securing together one pair of corresponding edges of said pieces of material, along a fold line, the opposite edges of said pieces of material being juxtaposed to each other; fastening means carried by one of said pieces of material, adjacent the said opposite edge thereof, for engagement with the said other fastening means in the overcoat neck portion or with the fastening

means on the free edge of the collar, to secure said piece either inside of the regular collar of the overcoat or else to the said free edge of the regular collar; and separable, cooperable fastening means on the said opposite edge of the other piece of material, for detachably securing the two halves of said opposite edge together in coextensive relationship.

2. The invention as defined in claim 1, in which the said one piece is wider than the said other piece and is provided with a collar facing suitable for being exposed to view when the pieces are superposed and folded in the form of a collar.

3. The invention as defined in claim 2 in which the collar facing comprises fabric.

4. The invention as defined in claim 1, in which the fastener means on the first piece comprises button holes.

5. The invention as defined in claim 1, in which the separable fastener means on the said opposite edge of the second piece comprises zipper elements.

6. The invention as defined in claim 1, in which there are separable cooperable fasteners adjacent the said opposite edge of the second piece and the adjoining portions of the first piece, to temporarily hold said pieces in superposed relationship.

7. In combination, an overcoat having a permanent collar on which there is a free edge, said collar being

provided with separable fastening means on its underside adjacent the free edge thereof, and having like, separable fastening means on the inside of the neck portion; a detachable overcollar for said overcoat, comprising a pair of segmental-shaped pieces of material disposed in superposed relation; means securing together one pair of corresponding edges of said pieces of material, along a fold line, the opposite edges of said pieces of material being juxtaposed to each other; fastener means carried by one of said pieces of material, adjacent to the said opposite edge thereof, for engagement with the separable fastening means of the overcoat to secure said piece either inside of the regular collar of the overcoat or else to the free edge of said collar, said one piece having at one side and on part only of its surface a collar-type facing providing added thickness to the piece; and separable, cooperable fastening means on the said opposite edge of the other piece of material, for detachably securing the two halves of said opposite opposite edge together in coextensive relationship.
